DESIGN FOR A SERVICE STATION

Robert Smith, Jr., Cleveland, Ohio, assignor to
Insulated Steel Construction Company, Cleve-
land, Ohio, a corporation of Ohio

Application May 16, 1934, Serial No. 51,808

Term of patent 7 years

To all whom it may concern:

Be it known that I, ROBERT SMITH, JR., a sub-
ject of the King of Great Britain, residing at
Cleveland, in the county of Cuyahoga and State
of Ohio, have invented a new, original, and or-
namental Design for Service Station, of which
the following is a specification, reference being
had to the accompanying drawing, forming part
thereof.

In the drawing, Figs. 1 and 2 are perspective
views respectively from the front and the front
quarter, of a service station showing my new de-
sign, and Fig. 3 is a typical horizontal section
of the same.

I claim:

The ornamental design for a service station, as
shown.

ROBERT SMITH, JR.
